UNITED STATES PATENT OFFICE.

WINN E. BROUGHTON, OF PEABODY, MASSACHUSETTS, ASSIGNOR TO THE TURNER TANNING MACHINERY COMPANY, OF PEABODY, MASSACHUSETTS, A CORPORATION OF MAINE.

LEATHER-WORKING MACHINE.

Application filed November 14, 1923. Serial No. 674,692.

This invention relates to machines for treating sheet material, such as hides, skins and leather. The invention is herein shown as embodied in a cheecking machine of the 5 type comprising a knife operative to slice portions from the thicker parts of a hide or skin, a drum by which the work is carried, and means for spreading work upon the drum to smooth out wrinkles. It is to be 10 understood, however, that in various aspects the invention is not limited to embodiment in a cutting machine of this type.

It is an object of the invention to provide an improved cutting machine which will be 15 especially efficient for performing operations such as cheecking hides and skins, and by the use of which superior work may be accomplished with minimum liability of injury to the work.

To this end, and in accordance with important features of the invention, there is provided a pressure member which is arranged to engage the work after it has been 20 spread out on a work support, such as a rotatable drum, the pressure member having a roughened surface to press and hold the work against the work support for the purpose of facilitating proper presentation of the work to a knife or other operating instrumentality. In the 25 illustrated construction, a power driven pressure roll co-operates with a rotatable drum on which the work is clamped to maintain the work smooth and free from wrinkles after it has been spread out on the drum 30 by spreading means, such as those referred to, and to feed the work to a reciprocating knife movable to draw its cutting edge through the work. Preferably and as illustrated, the pressure roll is fluted longitudinally and is located in close proximity to the cutting edge of the knife.

Other features of the invention and novel combinations of parts will be described in 35 the detailed specification and pointed out in the claims at the end of this specification.

Fig. 1 is a front elevation of a cheecking machine embodying this invention.

Fig. 2, a partial side elevation and section of the machine shown in Fig. 1, the section being taken on the line 2-2, Fig. 1.

Fig. 3, a side elevation of the machine looking toward the right in Fig. 1.

Fig. 4, a detail in vertical section on the line 4-4, Fig. 5, and

Fig. 5, a plan of the portion of the machine shown in Fig. 4.

Referring to the drawing, 10 represents a work support in the form of a segmental drum mounted on a shaft 12 journaled in upright frames 13, 14, erected upon a base 15. The drum 10 is provided with a stationary clamping member 16 with which co-operates a movable clamping member 17, between which the hide, skin or leather, herein termed "the work", is clamped to firmly secure it to the drum while undergoing treatment. The drum 10 has co-operating with it a spreading device illustrated as a cylinder or roll 20 provided with helically arranged blades or vanes 21, which are arranged to spread the portion of the work lying on the outer surface of the drum, laterally from about the center toward the opposite ends of the drum in a manner well understood, so as to take out the wrinkles in the work and to cause the work to lie flat or smooth on the drum, while it is being acted upon by a cutter or knife 22, which co-operates with the drum and with the work thereon to act on the thicker portions of the work, such as the neck portions of the hides or skins, and not to act on other portions thereof. The drum 10 also has co-operating with it a rigid gage or pressure roll 23, having a roughened work-engaging surface provided by longitudinally extended flutes or corrugations 24, which roll is located between the spreading cylinder 20 and the cutter or knife 22 and is arranged in close proximity to the latter to engage the work with a firm pressure uniform throughout its length along a line closely adjacent to the cutting edge of the knife.

The gage or pressure roll 23 is rotated in a direction the reverse of that of the drum and at the same or substantially the same surface speed of the latter, so as to function as a feed roll, which co-operates with the drum to assist in feeding the work to the knife 22 and thereby relieve the strain on the clamp 16, 17, and enable a minimum pressure to be applied to the work by the clamping member 17. Since the roll assists in feeding the work in co-operation with the drum, the clamping members 16 and 17 are

not depended upon to drag the work against the knife or cutter. Hence injury to the work through stretching of the same is avoided.

5 The gage or pressure roll 23 also serves to retain the work in the smooth or flat condition in which it is put by the spreading cylinder 20 and presents the work in this condition to the knife 22, thereby preventing 10 the work from being presented to the knife in a wrinkled condition and obviating the possibility of the work being cut up into strips or ribbons and consequently damaged.

The knife or cutter 22 may be reciprocated 15 as shown, by means of an elbow lever 26 (see Figs. 4 and 5), which is operatively connected with a main or driving shaft 27 by a reciprocating member 28 and a link 29. The main shaft 27 is provided as shown 20 with fast and loose pulleys 30, 31, (see Fig. 1) and is connected with the bladed cylinder 20 to drive the latter by a link chain 32 and sprocket wheels 33, 34, whereby the cylinder 20 is rotated in the same direction as the 25 drum so that their closely adjacent surfaces are moving in opposite directions thus enabling the cylinder to spread out the work on the surface of the drum.

The bladed cylinder 20 is connected with 30 the feed roll 23 by gears 36, 37, sprocket wheel 38, link chain 39 and sprocket wheel 40 (see Fig. 3), which arrangement rotates the feed roll 23 in a direction opposite to that of the drum so that the roll co-operates 35 with the drum in feeding the work.

The drum 10 is rotated from the main shaft 27 through a counter shaft 42 (see Figs. 1 and 2), which is connected with the main shaft 27 by a gear 43 and pinion 44, 40 and the counter-shaft 42 is provided with a pinion 45 shown in Fig. 3, which meshes with a gear 46 on the drum shaft 12 and is rendered fast and loose on the counter shaft 27 by a clutch of known construction, the 45 movable member 50 of which is actuated by a forked arm 51 on a rock shaft 52 provided with a crank 53, which is connected by a link 54 with a crank 55 on a shaft 56 provided with a foot treadle 57.

50 The clutch member 50 is moved into its out position by a spring 58 attached to an arm 59 on the treadle shaft 56.

The drum 10 is rotated in one direction, indicated by the arrow 100, and is stopped 55 at the end of each revolution by an automatic stop mechanism comprising an annular flange or ring 60 attached to the gear 46 and provided with a slot 61 into which is adapted to enter a projection 62 on an arm 63 fast on a rock shaft 64, which is provided with a segmental gear 65, which meshes with a segmental gear 66 on the rock shaft 52.

55 When the foot treadle 57 is depressed to throw in the clutch member 50, the pro-

jection 62 is withdrawn from the slot 61 and the drum is free to be turned one revolution. The projection 62 rides on the face of the ring or flange 60 until the drum has made a revolution, whereupon the slot 61 70 is brought into position to be entered by the projection 62, which is moved therein by the spring 58.

As soon as the drum is started, the operator can remove his foot from the treadle. 75 When the drum is started, the clamping member 17 is closed by a spring 70, and at or about the time the drum has made a revolution, the clamping member 17 is automatically opened by a cam 71 on the framework, which cooperates with a roller 72 carried by one member 73 of a toggle, whose other member 74 is connected with the movable clamping member 17 (see Fig. 3). It will be understood that the clamping 80 members 16, 17 are set in from the periphery of the drum so that there is no interference with the operation of the rolls or of the cutter 22. In introducing the work, the thinner portion is located for the operation 85 of the clamping members so that the thicker portion comes last and is dragged and fed 90 to the cutter 22.

The bladed cylinder 20 is yieldingly pressed against the work by spring 75 95 whose pressure or tension may be adjusted by nuts 76 in a known manner, and the feed roll 23 may be acted upon in a similar manner by springs 77 whose pressure or tension is regulated by nuts 78.

100 The knife or cutter 22 is mounted in a suitable carrier, which is adjustable on the frame of the machine by means of screws 80 extended into slots 81, to position the knife with relation to the drum, and may be firmly secured in its adjusted position by screws 82, 83 or in any other suitable manner.

The clamping member 17 is moved away 110 from the clamping member 16 a sufficient 115 distance to afford a wide opening for the operator to insert one half of the hide or skin into the drum and to withdraw his hands while the clamping member 17 is stationary in its open position, thereby 120 avoiding liability of the operator being injured by the clamping member 17.

One embodiment of the invention is shown, but it is not desired to limit the invention to the particular construction 125 shown.

What I claim is:

1. In a machine for cheecking hides and other similar pieces of work, in combination, 130 a rotatable drum to support the work, clamping mechanism carried by the said drum to secure the work thereto, a knife for operating on the work, a cylinder having helically arranged vanes to engage the work on said drum and spread it out on the 135

- latter before being presented to the knife by said drum, and a fluted roll arranged between said spreading cylinder and said knife for co-operation with the drum in presenting the work to the knife.
2. In a machine for cheeking hides and other similar pieces of work, in combination, a drum to support the work, clamping mechanism carried by said drum to secure the work thereto, a knife for operating on the work, a spreading cylinder co-operating with said drum to spread out the work thereon, a pressure roll arranged between the spreading cylinder and said knife and co-operating with the drum to feed the work to the knife, means for rotating said drum, means for automatically stopping the drum, and means for automatically operating said clamping mechanism to close and open the same.
3. In a machine for cheeking hides and other similar pieces of work, in combination, a rotatable support for the work, a knife for operating on the work, means co-operating with the work support to spread and smooth out the work on the work support, and means interposed between the said spreading means and said knife and co-operating with the rotatable work support for engaging the work with a firm uniform pressure to hold it in its smooth, spread-out condition while it is being acted upon by said knife.
4. In a machine for cheeking hides and other similar pieces of work, in combination, a rotatable support for the work, means for clamping said work to said rotatable support, a reciprocating knife co-operating with the rotatable support to cut the work thereon, means co-operating with the rotatable support to spread and smooth out the work thereon before the latter is presented to said knife, and a roll interposed between said spreading means and said knife and located in proximity to the latter to hold the work firmly on the rotatable support in its spread-out condition in close proximity to the cutting edge of said reciprocating knife.
5. In a machine for cheeking hides and other similar pieces of work, in combination, a drum to support the work, automatic clamping mechanism carried by said drum to secure the work thereto and to release the work at a predetermined point in the operation of the machine, a non-rotary tool co-operating with said drum to treat the work thereon, means co-operating with the drum to spread and smooth out the work on the drum prior to its being presented to said operating tool, and a roll interposed between the operating tool and said spreading
- means to press the work on the drum and hold it in its smooth spread-out condition thereon while it is acted upon by said operating tool.
6. In a machine for cheeking hides and other similar pieces of work, a rotatable drum for supporting work, an automatic clamping member for holding the work on the drum, a cutter movable to draw its cutting edge through the work, a member for spreading the work on the drum, and a roll located closely adjacent to the cutter and arranged to co-operate with the drum in presenting the work to the cutter.
7. In a machine of the character described, a rotatable work support, a member for clamping the work on the support, spring means for closing the member yieldingly on the work, a toggle for opening the clamping member to release the work at a predetermined point in the rotation of the work support, a cutter movable to draw its cutting edge through the work, and a roll located closely adjacent to the cutter and power driven to co-operate with the support in feeding the work to the cutter.
8. In a machine for cutting sheet material, a cutter, a rotatable work support, a member for spreading the work on the work support, and a pressure member between the spreading member and the cutter and having a roughened surface acting to press and to hold the work against the work support and rotatable in a direction the reverse of the work support to co-operate therewith in feeding the work to the cutter.
9. In a machine for cutting sheet material, a knife, a work support, a member for spreading and smoothing out the work on the support, and a pressure member between the spreading member and the cutter and closely adjacent to the cutter, said pressure member operating to apply a firm pressure to the work uniform throughout its length to maintain the work in the smoothed out condition effected by the spreading and smoothing member for presentation to the knife.
10. In a machine for cutting sheet material, a cutter, a rotatable work support, a member for clamping work on the support, a member rotatable in the same direction as the work support for smoothing and spreading the work on the support, and a fluted roll rotatable in a direction the reverse of the work support and co-operating therewith in feeding the work to the cutter.

In testimony whereof, I have signed my name to this specification.

WINN E. BROUGHTON.
